Fribourg, Switzerland

Filed Sept. 14, 1964, Ser. No. 81,716

Term of patent 14 years

(Cl. D15—11)

FIG. 1.

FIG. 2.

FIG. 3.

FIGURE 1 is a perspective view of a restaurant booth seat incorporating my new design, the seat and back not shown being the same in appearance as the seat and back shown;

FIG. 2 is an end elevational view taken from the right of FIG. 1; and

FIG. 3 is an end elevational view of a modified form of the design of FIGURE 1 illustrating the seat as a single unit.

The seat and backrest cushions not shown in FIG. 3 are like those shown in FIG. 1; the end of the seat not shown being like the end shown while the back of the unit is plain and unornamented.

The dominant features of my design reside in those portions shown in full lines on the drawing.

I claim:

The ornamental design for a restaurant booth seat or similar article, substantially as shown and described.
